CLAIM

We claim the ornamental design for an electronic device for
visual impaired people, as shown and described.

DESCRIPTION

FIG. 1 is a front elevational view of an electronic device for
visual impaired people according to the present invention.

FIG. 2 is a rear elevational view of the electronic device for
visual impaired people of FIG. 1.

FIG. 3 is a left side elevational view of the electronic device
for visual impaired people of FIG. 1.

FIG. 4 is a bottom perspective view of the electronic device
for visual impaired people of FIG. 1.

FIG. 5 is a top perspective view of the electronic device for
visual impaired people of FIG. 1.

FIG. 6 is a top perspective view of the electronic device for
visual impaired people of FIG. 1 in a condition of use; and,

FIG. 7 is a top perspective view of the electronic device for
visual impaired people of FIG. 1 in a condition of use showing
the design in an alternate position with some of the broken
line elements seen in other views removed.

The broken lines represent environmental elements only and
form no part of the claimed design.

1 Claim, 7 Drawing Sheets
